UNITED STATES PATENT OFFICE.

JOHN F. REMY, OF CRESTLINE, OHIO, ASSIGNOR TO THE BURCH PLOW WORKS CO., OF CRESTLINE, OHIO.

PULVERIZER.

1,331,722.

Specification of Letters Patent.

Patented Feb. 24, 1920.

Application filed January 18, 1919. Serial No. 271,840.

To all whom it may concern:

Be it known that I, JOHN F. REMY, a citizen of the United States, residing at Crestline, in the county of Crawford and 5 State of Ohio, have invented certain new and useful Improvements in Pulverizers, of which the following is a specification.

This invention relates to soil pulverizers and rollers of that type which employ a plurality of gangs of disks arranged one in advance of another, the forward gang being mounted in the main frame, and the object of the invention is to provide simple, inexpensive and efficient means whereby sufficient pressure will be exerted upon the rear gang to hold the same to its work.

The invention is illustrated in the accompanying drawings and consists in certain novel features which will be hereinafter first 20 fully described and then more particularly pointed out in the claims.

In the drawings:

Figure 1 is a perspective view of a pulverizer having my improvement applied 25 thereto;

Fig. 2 is an end elevation of the same;

Fig. 3 is a rear elevation of one end of the pulverizer.

The main frame 1 may be of the usual or 30 any preferred construction and is illustrated as provided with a draft tongue or pole which is supported upon a steering truck 2 at its front end which truck may be dispensed with if the pulverizer be drawn by 35 a tractor. The frame is also equipped with a spring standard 3 supporting a driver's seat 4. To the ends of the frame, I secure hangers or brackets 6 having journal boxes 7 at their lower ends in which is mounted 40 the axle of the forward gang of pulverizer disks 9. A dust cap 8 is arranged over the end of the axle and is bolted to the journal box 7 as shown at 80. The disks may be of any well-known or preferred form and are 45 illustrated as having their circumferential surfaces converging from their ends toward their centers, so as to provide central annular ridges 10 which will take into the ground and thoroughly cut up and pulverize the 50 same. To the hangers or brackets 6 I pivotally secure the front ends of lever arms 11 having their rear ends formed into sleeves or collars 12 which encircle the axle of the 55 rear gang of disks 14. A dust cap 13 fits over the end of the axle and is secured to the

collar 12, as shown at 130. The collar 12 is provided at its inner end with a depending lug 15 and a similar lug 16 is provided on the under side of the spacing and bearing sleeve 17, disposed about the axle between 60 the end disks 14 and the inner end of the sleeve 12. A bolt 18 is inserted through the lugs 15 and 16 so as to hold the members 12 and 17 together. Upon the upper sides of the sleeves 12 and 17 are lugs or ears 19 through which is inserted a pivot bolt 20, 65 and said bolt is engaged between the said lugs or ears by an eye 21 on the lower rear end of a rod 22 which passes upwardly and forwardly and plays freely in a combined 70 stop and guide shown as an eye 23 secured in the upper portion of the adjacent bracket or hanger 6, but may be provided on the lower or rear portion thereof. A spring 24 is coiled around the rod 22 between the eye 75 23 and a collar 25 fitted loosely upon the rod and held in any adjusted position by a set screw 26, as will be readily understood. Obviously, by adjusting the collar, the tension of the spring may be regulated as desired. 80

It is thought that the uses and advantages of my invention will be readily understood. In order to effectually perform its intended work, the pulverizer must exert a certain amount of pressure upon the ground, in order that the disks will properly enter the soil and pulverize the same. The weight of the main frame is borne principally by the front gang of disks, so that sufficient pressure is applied to the said front gang of disks 90 to accomplish the desired results. Ordinarily, however, the rear gang of disks exerts no pressure except that due to its own weight and if the soil should be very hard or if obstructions be encountered, the rear 95 gang will not properly penetrate the soil and it is necessary to drive over the field several times before the soil is brought into proper condition. By providing the rod 22 and the spring coacting therewith, I accomplish the 100 desired result and hold the rear gang to its work so that it will properly penetrate the soil and at the same time will yield to large rocks or similar obstructions sufficiently to avoid damage to any of the parts of the 105 machine.

Having thus described the invention, what is claimed as new is:

1. The combination with a pulverizer comprising a frame, and a gang of disks 110

mounted in said frame, of supporting arms pivoted to the lower portions of the end members of the frame and extending rearwardly therefrom, a gang of ground-engaging members supported by and extending between the rear ends of said supporting arms, a relatively stationary guide on the end of the frame above the adjacent pivoted supporting arm and in advance of the gang of ground-engaging members, a rod pivoted at its lower rear end to the adjacent supporting arm and extending upwardly and forwardly therefrom and having its upper forward end playing freely in the guide, an adjustable stop on said rod, and a spring coiled around the said rod between said stop and the guide on the frame and exerting downward pressure on the supporting arm.

2. In a pulverizer, the combination of a frame, a gang of disks mounted in said frame, a guide on the frame, supporting arms pivoted at their front ends to the frame and extending downwardly and rearwardly therefrom, a second gang of disks mounted between the rear ends of said sup-

porting arms, a rod pivoted at its lower rear end to the adjacent supporting arm and extending upwardly and forwardly therefrom and playing freely in the guide on the frame, a collar adjustably mounted on said rod, and a spring coiled around the rod between said collar and said guide.

3. In a pulverizer, the combination of a frame, a gang of disks mounted in said frame, supporting arms pivoted at their front ends to the frame and having collars at their lower rear ends, a gang of disks mounted between the rear ends of said arms, sleeves interposed between the collars and the end disks of the gang of disks, means for connecting the sleeves with the collars, guides on the ends of the frame, rods pivoted at their lower ends on said connecting means and playing at their upper ends freely in the guides on the frame, and a spring coiled around each rod between the respective guide and supporting arm.

In testimony whereof I affix my signature.

JOHN F. REMY. [L. S.]
